UNITED STATES PATENT OFFICE.

ISAAC MANDEL, OF NEW YORK, N. Y.

HYGIENIC GARBAGE-RECEPTACLE.

1,253,620.

Specification of Letters Patent. Patented Jan. 15, 1918.

Application filed May 25, 1914. Serial No. 840,887.

To all whom it may concern:

Be it known that I, ISAAC MANDEL, a subject of the King of Hungary, residing in New York city, county and State of New York, have invented certain new and useful Improvements in Hygienic Garbage-
Receptacles, of which the following is a specification.

This invention relates to garbage cans and the like and particularly to such as are adapted to be emptied in a sanitary manner.

One object of my invention is to provide slidably mounted tops and bottoms for co-operating garbage cans and means for automatically closing the tops and bottoms after the contents have been transferred from one to another.

Another object of my invention is to provide a simple and improved can specially intended for household use and adapted to be readily superimposed on a larger can without being inverted, the bottom of one co-operating with the top of the other to open the cans which embody automatic means for closing the top and bottom as the smaller can is removed from the larger one.

Other objects and advantages of my invention will be set forth hereinafter, and in order that my invention may be thoroughly understood, I will now proceed to describe the same in the following specification and then point out the novel features thereof in appended claims.

The nature, characteristic features and scope of the invention will be more fully understood from the following description taken in connection with the accompanying drawings, forming part hereof and in which:

Figure 1 is a view in perspective of a relatively small or household receptacle, arranged and constructed in accordance with my invention.

Fig. 2 is a view in perspective of a relatively large or street receptacle with which the smaller receptacle is adapted to co-operate.

Fig. 3 is a central cross-sectional view through the upper section of Fig. 2.

Fig. 4 is a central cross-sectional view of two cans partly superimposed one upon the other.

Fig. 5 is a sectional view of two cans superimposed one upon the other.

Figs. 6, 7 and 8 are diagrammatic sec-

tional views showing a can being placed over another can.

Referring to the drawings 1 designates the house can and 2 designates the larger or street can, constructed of any suitable material, preferably galvanized sheet metal and provided on opposite sides intermediate its ends with handles 3. A cover 4 is connected to one side, preferably the rear side of the can, by hinges 5 and is provided with a knob 6 for raising the cover 4 when desiring to place garbage into the can 1. Guides 7 are provided on opposite sides of the can 1 serving as supports for the can and are adapted to receive the bottom 8 of can 1. Cylinders 9 are provided at the intersection of the side and rear walls and extend the entire height of said walls and each cylinder contains a spring 10 having one end secured to the upper end of the cylinder and the other end secured to a flexible metal cord 11 having its other end fastened to bottom 8. A grooved roller 12 serves as a guide for the cord 11. A projection 13 is secured to the rear of bottom 8, the purpose of which will hereafter be more fully described.

In Fig. 2, I have there shown a street garbage receptacle, provided with slidably mounted top and base said top and base being slidable in opposite directions. The construction of the side walls and base is similar to the construction shown in Fig. 1 and hereinbefore described. In order to slidably operate the top 15, I provide guides 14 on opposite sides of the can adjacent the top thereof and adapted to receive a top 15. Cylinders 16 are provided at the intersection of side walls and front wall and extend the entire height thereof and are adapted to contain springs 17 having one end of each secured to the base of the cylinders 16, their other ends are secured to flexible metal cords 18, which are secured to opposite sides of the top 15. Grooved rollers 19 are secured at the top of cylinders 16 and serve to guide the cord 18.

A projection 20 projects from the front wall adjacent the top 15 of the can and engages the base projection 13, a higher projection 20' formed to the top 15 adjacent the front of the can 2 and serves to engage the rear wall of the can 1.

The operation of the device is as follows:

When it is desired to place garbage into

the house receptacle, the cover is lifted and the garbage is dropped into the receptacle. In the evening or whenever the receptacle is filled, the same is carried to the larger or 5 street garbage receptacle and placed with its rear wall adjacent the bottom thereof against the upper portions of the front wall of the can 2, so that projection 13 will engage projection 20 of the front wall of can 1, and the projection 20' will engage the 10 rear wall of receptacle 1. The upper can is then forced backward thereby simultaneously opening the top and base of receptacles 2 and 1, respectively. The contents of receptacle 1 having dropped into 15 receptacle 2, the smaller receptacle is removed from the top of the receptacle 2 and the base and top are due to their spring and cord arrangement returned to their normal 20 positions.

I have here shown a physical embodiment of my invention as best known to me at the present time for practising the same, obviously details of construction and minor arrangement of parts may be made without departing from the spirit of the invention. 25

I claim:

1. A transmitting receptacle for garbage having tapering sides, a hinged lid at the 30 top, cylindrical edge pockets, a sliding bottom, springs mounted in the cylindrical edge pockets, flexible cords connecting the

springs to the slidable bottom tending to hold the bottom closed, and a pair of spaced guideways constituting supports for the receptacle and guides for the slidable bottom, 35 said slidable bottom having a downwardly extending projection by which it may be opened.

2. In combination with a receiving receptacle having a sliding top provided with an upwardly extending rib or projection, and automatic means tending to close the top, of a transmitting receptacle having tapering sides, a hinged lid at the top, cylindrical edge pockets, a sliding bottom, 40 springs mounted in the cylindrical edge pockets, flexible cords connecting the springs to the slidable bottom tending to hold the bottom closed, and a pair of spaced guideways constituting supports for the receptacle and guides for the slidable bottom, said slidable bottom having a downwardly extending projection adapted to coöperate with the rib or projection on the top of the 45 receiving receptacle, whereby the top and bottom of the respective receptacles may be opened concurrently as the receptacles are superposed.

In testimony whereof I affix my signature 50 in presence of a witness.

ISAAC MANDEL.

Witness:

ALEX. MANDEL.
